REGISTERING BANK

Harry T. Kingsbury, Keene, N. H.

Application September 23, 1936, Serial No. 102,232

13 Claims. (Cl. 235—100)

This invention relates to certain improvements in registering banks which are employed for the deposit and reception of coins of various denominations, along with means operated upon the insertion of a coin for registering the total value of all coins so deposited.

Structures for this purpose have been disclosed and claimed in my prior Patents Nos. 1,939,353 and 2,022,422.

10 The present invention includes certain simplifications of structures set out in said prior patents, and in a particular association of parts by which the coin-sizing and the register-operating elements are coordinated.

15 Illustrative ways of practicing the present invention are set out on the accompanying drawings, in which:

Fig. 1 is a face view of the indicators in the registry system.

20 Fig. 2 is a rear view of the casing which surrounds the major portions of the operating mechanism.

Fig. 3 is an upright diametrical view through the central axis, on a larger scale than that of Figs. 1 and 2.

Figs. 3a, 3b and 3c are details of parts.

Figs. 4 to 10 are sectional views, on the same scale as Figs. 1 and 2, substantially on lines 4—4 to 10—10 respectively of Fig. 3.

30 Figs. 11 and 12 are diagrams of operation of the coin-sizing elements and certain associated structures.

Figs. 13 to 16 are perspective views of the register-controlling structures.

35 Fig. 17 is a face view of the cam shown in Figs. 8 and 12.

Figs. 18 and 19 are perspective views of details.

Fig. 20 is a view of a modified form of structure, corresponding essentially to the showing of Fig. 5.

40 Fig. 21 is a further sectional view of the modified form, corresponding substantially to Fig. 6.

Fig. 22 is a fragmentary view corresponding to Fig. 20, but showing the parts in another operated position.

45 Fig. 23 is a perspective view of the rocker of Figs. 20 and 22.

In these drawings, the outer casing and the lower box for receiving coins have been assumed to be substantially identical with those exemplified in my aforesaid patents, and may be provided with the automatically-locked and -released access door disclosed therein.

50 This lower collection box 10 is sealed at its top to a fixed cylindrical casing 11 having an integral

rear wall 12 and a front bezel 13 which slips over and is secured to the front edge of the cylindrical wall 11, and extends inwardly for engagement with the glass disc 14 covering the face of the indicator dial. Brackets 15 are provided on the 5 interior of the cylindrical wall 11 to determine the distance of this glass from the rear wall 12, and its proper positioning in this outer casing.

The dial 16, as shown in Figs. 1 and 3, comprises an outer circular scale which is divided 10 from "0" to "95" and cooperates with a long hand, as described hereinafter, for registering the value of coins by cents. A circular inner scale bears indicia from "0" to "9", and cooperates with a short hand for indicating dollars. 15

At the rear of the casing 11 is provided a crank arm 17 having a handle knob 18 thereon, by which the various parts may be rotated and thus actuated.

Many of the structures within the casing 11 move about an axis concentric with the casing, this axis being provided by a shaft 20 having a portion of large diameter affording bearings for certain revoluble devices for accomplishing the coin-sizing and registering operations. The 25 shaft also has a flange 20a with a notch in its periphery for providing a driving connection between this shaft and a register ratchet, as will be described hereinafter more particularly with reference to Fig. 5 hereof. The reduced end 20b of 30 this shaft receives the long hand C, which has a flange to provide a force-fit with the shaft, so that these parts turn together.

The short hand D is rigid with an eyelet or dollar shaft 21 which fits around the shaft portion 20b, and extends through the dial plate 16. This eyelet 21 is fixed at its inner end to the dollar ratchet 22, parts of which are shown in Figs. 3, 4 and 5.

A friction washer 23, which may be of paper, 40 bears against the inner or rear face of the dollar ratchet 22, and in turn receives the peripheral flange 24a of a dished friction member 24 which is provided (Figs. 3 and 3b) with a central aperture to receive the shaft portion 20b, and with an 45 eccentric rearwardly struck lug 24b. A friction-clutch pressure spring 25 has a central aperture by which it is guided from the shaft 20, and is provided with a plurality of radially extending spring pressure arms 25a, each of which preferably has a pressure-hump formed thereon for engagement with the rear surface of the friction member 24 (see Figs. 3, 3c and 4). The lug 24b fits between two of the arms 25a. The central annular portion of the spring structure 25 bears 50 55

against the forward surface of the flange 20a, and thereby the spring structure is held in tensed condition.

The flange 20a bears at its rear surface against the front surface of the penny or cents ratchet 26 which is notched at its periphery, in this illustrative form for United States currency, to provide one hundred teeth thereat (Fig. 5). This penny ratchet is mounted on the shaft portion 20, 10 and has a forwardly directed lug 26a which engages a notch 20c (Figs. 3 and 5) of the flange 20a, and extends beyond the front surface of the flange 20a to engage between two of the arms 25a of the spring structure 25. Thus, a driving relation 15 is produced between the penny ratchet 26, through the lug 26a, which extends on the one hand through the flange 20a and shaft portion 20b to the long hand C, and on the other hand extends from lug 26a to the spring structure 25 20 and thus by lug 24b to the friction member 26. This penny ratchet 26 also has a forwardly struck lug 26b which operates for transferring registration to the dollar ratchet 22 as will be set out hereinafter.

25 A second friction disc 27 bears against the rear surface of the penny ratchet 26, and likewise may be of tough paper or like material.

At the rear of the second friction washer 27 is the mounting plate 28 for the register-controlling 30 pawls (Figs. 6 and 7). Preferably, in this form of construction, the plate 28 has a forwardly extending annular portion 28a (Figs. 3 and 7) for engagement with the friction member 27 adjacent the periphery thereof.

35 This supporting plate 28 is provided with a plurality of register-controlling pawls 30a, 30b, 30c, 30d, 30e, equal in number to the number of coins which are to be automatically registered by the apparatus. In the present instance, it is assumed that United States coins of the denominations of one, five, ten, twenty-five and fifty cents are to be so registered and indicated. Each of these pawls 30a . . . 30e (see Figs. 6 and 18 for an example) is located at the front face of the 40 mounting plate 28, and has a rearwardly extending lug 30m which projects through a hole in the supporting plate 28 to provide a pivot for the rocking movement of the correspondent pawl. Further, each of these pawls has an inturned portion 30n located opposite a corresponding aperture 30x (Fig. 7) in the plate 28, and each pawl 45 also has a curved outer edge for engaging a detent, as described hereinafter.

The supporting plate 28 has notches 28b, 28c, 50 28d, 28e, 28f at its periphery, whose relative location and effects will be described more in detail in conjunction with Figs. 11 and 12, and the statement of operation. Each of these notches 28b . . . 28f is provided (as marked for notch 60 28c in Fig 7) with an inward transition 28k from the adjacent portion of the extreme diameter of the plate 28, a relatively short circular arc 28m of a lesser diameter, and a terminating ramp 28r having its surface arranged substantially in a 65 plane at an angle to the axis of the shaft portion 20. The supporting plate 28 provides, between these notches, cam portions 28k, 28l, 28m, 28n, 28p, which are of lengths equivalent to the denominations of coins and are effective for permitting 70 corresponding movement of the totalizing member, as described hereinafter.

Rearwardly of the supporting plate 28 is provided a pawl actuating cam 31 (Figs. 3, 8, 12 and 17) which has a central aperture 31a fitting the 75 shaft portion 20 to be guided thereby. This cam

31, in this illustrative form, has the four humps 31b, 31c, 31d, 31e spaced along its periphery at selected points thereof, and a longer hump 31f. The purpose and relative position of these humps is set out hereinafter in connection with Fig. 12 5 and the description of operation. This cam 31 also has a rearwardly extending apertured elevation 31m and an apertured lug 31n struck at its rear surface.

At the rear of the cam 31 (Figs. 3 and 8) is the 10 end wall 32 of the revoluble drum which has a peripheral wall 33. The end wall 32 of this drum has a number of elevations 32a thereon, which are arranged at greater radii from the axis of the shaft portion 20 than the periphery of the 15 cam 31, and which extend to the supporting plate 28 and preferably are secured thereto as by spot welding, whereby to provide a stiff structure surrounding the cam 31, and guiding the latter against axial rocking or translational movements. 20 The end plate 32 also has an arcuate slot 32b (Fig. 8) for receiving the parts 31m and 31n of the cam 31, and permitting the requisite peripheral movement of this cam 31. This end wall 32 also preferably has apertures 32c into which the 25 ends of the ramp portions 28r may extend, thus providing for a smooth operation during the course of the registering operation, as will be described hereinafter. The peripheral wall 33 of this revoluble drum has a coin-receiving aperture 30 33a which, when all parts of the sizing and registering mechanisms are at initial position, is presented opposite the coin aperture 11a (Figs. 9 and 10) in the outer cylindrical casing wall 11. This peripheral wall 33 also has a further aperture 33b which is substantially diametrically opposite from the aperture 33a. Fixed rigidly within the revoluble drum is a wall structure 34 providing a wall 34a which may be employed in coin sizing; it is preferred to accurately locate this 40 wall structure 34 by having the feet 34b thereof spot welded to the end wall 32 of the drum, and preferably the wall structure has a portion 34k projecting into the aperture 33a for better guidance to the coin into the pocket formed by the 45 end wall 32 and the wall structures 34. This wall structure has a forwardly turned circular flange 34c formed integrally therewith, to provide a pivot for the coin-sizing rocking structure 35. This rocking structure includes a nose 35a which 50 projects into the apertures 11a, 33a when the parts are in initial position, and thus engages the casing 11 to bring the rotatable system to a standstill at the completion of each coin-depositing rotary movement. The coin-sizing structure 55 35 also comprises the three lugs 35b which assist in determining the correct position of a coin which has been inserted, and thereby assuring a proper sizing thereof. The end 35c of the sizing structure 35 receives a link 36 which likewise 60 engages the aperture of the projection 31m of the cam 31, whereby the cam is rocked in a proportion dependent upon the rocking movement of the sizing structure 35.

The return of the cam structure, following such 65 a rocking movement, is assured by a torsion spring 37 having a coil guided by the shaft portion 20, and having one end engaged with the lug 31n of the cam and the other portion engaged about a lug 34x on the wall structure 34, as indicated in 70 the dotted lines of Figs. 8 and 9.

The rear wall 12 of the casing has a circular aperture 12a at its center for receiving the forwardly depressed central portion 11a of the handle 17 (Figs. 2 and 3), this central portion in turn 75

having an aperture for receiving and guiding the shaft portion 20. Inside, and thus at the front surface of the end wall 12, is provided the radial driving arm 40 (Figs. 3 and 10) which has an aperture for fitting around the shaft portion 20, and has the lugs 40a which extend rearwardly and through apertures in the cup 17a, and are clinched behind the rear wall of the latter whereby to provide a fixed driving relation between the crank arm 17 and the radial driving arm 40. The outer end of the driving arm 40 has a pair of walls 40b which extend forwardly. This driving arm also provides a pivot structure 40c for the direct controlling pawl 41 which has a biting point 41a for engaging the inner surface of the peripheral wall 11 and thus preventing retrograde movement of the crank handle 17, 18. The proper engagement of the pawl 41 is maintained by a spring 42 which engages on the one hand with the lug 41b of the pawl, and on the other hand with the inner end of a wall 40b, being retained by the lug 40ba.

As illustrated in Figs. 9 and 10, the radial driving member 40 extends into the aperture 33b of the revoluble drum structure, and thus turns the same in rotation.

Fixed within the peripheral wall 11 of the outer stationary casing, as by spot welding, is a support 11m (Fig. 5) which pivotally receives one end of the register-controlling lever 45 (Figs. 5 and 13 to 16), whereby this lever 45 is permitted to rock toward and from the axis of the shaft portion 20b, and also permitted at its free end to have a movement in a relatively axial direction with regard to the adjoining penny ratchet 26. The lever 45 has an inwardly extending free end 45a for receiving the spring 46 which is engaged with the structure 11m so that the spring operates to press the free end of lever 45 constantly inward and also to press this end relatively toward the end surface 32 of the revoluble drum. The lever 45 also has the axially extending lug 45b which may rest against the front surface of the supporting plate 28 (Fig. 13) or against the end surface 32 (Fig. 15), according to the position taken by the lever 45 in its movements toward and from the surface 32; and this lug 45b may also rest against the peripheral edge of the supporting plate 28 (Fig. 14) or may be received by one of the notches 28b . . . 28f and then engage (Fig. 15) between two teeth of the penny ratchet 26.

The transfer from the penny ratchet 26 to the dollar ratchet 22 is accomplished in this form of the invention by providing the dollar ratchet 22, in correspondence with the ten divisions on the dial 16, with ten rearwardly extending lugs 22a (Figs. 4 and 5), any one of which may be engaged and detained by the shoulder 50a of the resilient arm 50 which is secured to a fixed structure, such as the inwardly extending lug 16a of the dial 16 (Figs. 3 and 4). The lug 26b of the penny ratchet 26, during the clockwise movement of the latter (Fig. 5) is so constructed and arranged that it may engage the actuator lug 50b of the arm 50 and thereby press the latter outwardly for disengaging the hook portion 50a from the lug 22a with which it has been engaged, thereby releasing the dollar ratchet 22 from its former detention by the spring arm 50, so that a frictional driving is accomplished. During this driving, the lug 26b moves past the position of the actuator portion 50b, so that the hook 50a is released and moves radially inward to engage the next lug 22a.

Within the reception box 10 for the coins, the

fixed cylindrical casing 11 has a further aperture 11x, which is located in the same plane as the aperture 11a, and through which the coins are ejected from the revoluble drum, so that they fall into the reception box 10. The peripheral wall 11 is formed at one end of the aperture 11x with a ramp 11y for engaging the nose 35a and forcing the latter inwardly, whereby to avoid stoppage of the drum at an undesired point of the revolution.

The operation of this structure is as follows:

It is the purpose of the apparatus to receive coins of various denominations, and by the simple operations of inserting the coin and rotating the crank arm 17, to effect a registration of the amount of the coin, and to discharge this coin into the deposit box 10.

The normal position of the sizing lever 35 is indicated in Fig. 9, from which it will be seen that the nose 35a engages the end of the wall 20 which defines the slot 11a in the casing 11, through which the coin is to be inserted. This nose 35a therefore prevents movement of the crank arm 17 in a relatively clockwise direction in Figs. 1 and 4 to 12 inclusive (corresponding to 20 a counter-clockwise direction in Fig. 2). Movement of the crank arm in the other direction is inhibited by the engagement of the pawl 41 with the inner wall of the housing 11. That is, it is necessary to depress the nose 35a, so that it can slide along the inner wall of the casing 11, in order to permit rotation of the several parts including the crank arm 17.

The first operation performed, in moving the parts from this initial position, is that of inserting a coin through the apertures 11a, and 33a, which are in alignment in this initial position (Figs. 9 and 11). The advancing edge of the coin, as it is pressed into the structure, encounters the lugs 35b and causes the sizing lever 35 to rock in a relatively clockwise direction in Figs. 9 and 11. The coin is guided by the walls of the apertures 11a, 33a, by the forward wall 34a of the coin pocket, and by the several lugs 35b, engaging its edges under various conditions with respect to the size of the coin, the direction in which it is pressed in, etc.

The introduction of the coin depresses the nose 35a, and the crank arm 19 can now be rotated. As soon as rotation begins, the pawl 41 operates to prevent any retrograde movement. When the coin has been carried a sufficient distance past the position of its introduction, so that it will not be ejected by the action of the spring 37, it may be released by the operator's hands. Such a position of the parts is shown in Fig. 11, in which a twenty-five cent piece has been inserted until its outer periphery is substantially coincident with the circular walls of the casing 11, and the sizing lever 35 has thus been moved to the full line position of Fig. 11, which is marked "25¢". Since a ten cent piece is smaller, the rocking movement of the sizing lever is less, while for a fifty cent piece, the movement is greater: such positions are indicated in dotted lines in Fig. 11, and it will be understood that each particular coin is of a characteristic diameter, so that the sizing lever 35 tends to move to an angle which is characteristic of the particular coin.

The rotation of the crank 17 carries with it the radial arm 40, the revoluble drum having the end wall 32, the parts of the coin pocket including the pivot 34c of the sizing lever 35, and the supporting plate 28. During the initial portion of the movement of the crank arm 17, the coin is

brought into engagement with the inner wall of the casing 11 and is pressed backward against the two lugs 35b most closely adjacent the pivot 34c, so that all coins move to this position, regardless 5 of the condition under which they were inserted in the machine. This results in the definite positioning of the sizing lever 35 corresponding to the characteristic diameter of the particular coin. Thereafter, the coin is caused to move with 10 its periphery in contact with the inner surface of the casing 11, so that this characteristic position of the sizing lever 35 is maintained.

The rocking movement of the sizing lever 35 operates through traction on the link 36 to effect 15 a coordinated rocking of the cam 31, so that the humps on this cam are selectively positioned opposite the pawls 30a . . . 30e. In the illustrated structure, which is utilized for coins of the denominations of one, five, ten, twenty-five and fifty cents, the arrangement of the pawls and of 20 the cam is illustrated in Figs. 6, 8, 12 and 17. When a one cent piece is thus properly positioned, the hump 31e is positioned beneath the lug on pawl 30a (along radius e, Fig. 12). With a five 25 cent piece, the hump 31d is positioned beneath the lug of pawl 30c (radius f in Fig. 12). With a ten cent piece, the hump 31e is positioned beneath the lug of pawl 30b (radius f in Fig. 12). With a twenty-five cent piece, the hump 31c is positioned 30 beneath the lug of pawl 30d (radius l in Fig. 12). With a fifty cent piece, two humps are presented, the hump 31b being opposite the lug of pawl 30d (radius l in Fig. 12), while the hump 31f is opposite the lug of pawl 30e (radius p in Fig. 12). 35 Thus, for each coin, a particular selection is made among the pawls. Since the coin is inserted at initial position, the several angles have been designated in Fig. 12 as not involving relative rotation of the supporting plate 28 from initial 40 position, and in effect, therefore, the radius a designates a normal or starting line. That is, when a one cent piece is introduced, an angular movement of the cam 31 occurs so that the hump 31e moves in a relative clockwise direction with respect to the supporting plate 28, until this hump lies along the radius e, and correspondingly for 45 other coins.

In this initial position of the parts, the lug 45b of the detent pawl 45 is engaged with a tooth 50 of the penny ratchet 26, and is resting on the end surface of the supporting plate 28 (position of Fig. 13).

If a one cent piece has been positioned in the machine, the movement of the crank arm 17 causes rotation of the revolute drum. Since the 55 coin is maintained in the coin pocket, the cam 31 moves at the same rate as the revolute drum, and is maintained in its relatively rocked position as aforesaid, that is, with the hump 31e beneath the lug of pawl 30a. The lug 45b holds the penny ratchet 26 against being driven through the friction member 27 (Figs. 3, 6 and 13), and thus the long hand C remains in its former position opposite the dial 16.

60 Ultimately, during the movement of the revolute drum, the pawl 30a comes opposite the lug 45b and presses this lug away from the shaft 20 until the lug is free of the penny ratchet 26. The penny ratchet is then carried in rotation by the 65 action of the friction member 27. Immediately thereafter, however, the sharp nose of the pawl 30a releases the lug 45b again, and the latter again engages the ratchet 26 after the latter has advanced by a single tooth: it will be noted that 70 this occurs at the notch 28b (Figs. 6 and 7).

so that the lug 45b can immediately return to regain its detaining position. Shortly thereafter, during the continued movement of the revolute drum, the next ramp 28r will raise the lug 45b and restore it to a position on the end surface of 5 the supporting plate 28.

When a larger denomination of coin is inserted, so that the movement of the penny ratchet 26 must be greater than that of a single tooth, then a different selection of the humps on the cam 10 31 occurs as described above. During the movement of the rotatable drum, ultimately the selected pawl (such as the pawl 30b in Figs. 12 and 14) comes opposite the lug 45b and presses the latter outward away from the axis of the shaft 15 portion 20, until the lug 45b is beyond the peripheral edge of the supporting plate 28. The spring 46 now operates to rock the detent lever 45 in a relatively axial direction with respect to the shaft portion 60, that is, in a downward direction in Fig. 14 until the lug 45b rests against the surface of the drum end wall 32. It will be seen from Figs. 5, 12 and 14 that the lug 45b has thus been disengaged from the penny ratchet 26, and is being held out of such engagement by a larger 20 diameter portion of the periphery of the supporting plate 28.

As the crank arm 17 is turned further, the revolute drum continues its movement and the supporting plate 28 operates through the friction 30 member 27 to move the penny ratchet 26 and thus the long hand C through the shaft portion 20b as described above. The peripheral lengths of the outer peripheral cam portions of supporting plate 28 are constructed in such a manner that 35 their arcuate lengths, from the point at which a pawl 30b, 30c, 30d is operative as described for Fig. 14, to a following notch 28c, 28d, etc., respectively represent a number of teeth on the penny ratchet 26 equal in number to the denomination 40 of the coin which has operated in the sizing operating to effect a selection of the proper pawl. Thus, after the revolute drum has turned through an angle representing such a number of teeth, the lug 45b is pressed inward toward the 45 shaft portion 20 by the spring 46, and again comes into engagement with a tooth on the penny ratchet 26, so that the penny ratchet is detained again and held against frictional drive through the member 27 during the remaining course of movement of the revolute drum: this engagement of the lug 45b with the penny ratchet is illustrated in Fig. 15.

During the further movement of the revolute drum, however, the ramp 28r corresponding to the 55 particular notch is presented to the end of the lug 45b, and thus a further relatively axial movement is given to this lug and it is thus moved (for example, raised from the position of Fig. 15 to the position of Fig. 16) so that the lug is returned 60 to its initial position against the end surface of the supporting plate 28, as shown in Fig. 16. It will be noted that this axial movement results in a sliding of the lug along the tooth with which it is then engaged, but without any releasing of 65 the penny ratchet 26. It will be noted that, in some instances, further notches, such as the notches 28b, 28e, are brought opposite the lug 45b: in such cases, the lug drops from the end surface of plate 28 to the end surface 32 of the 70 drum, and then is raised by the following ramp 28r, but always maintains its detaining relation with the penny ratchet 26.

With the sizing and registering of a fifty cent piece, the lug 45 is moved from the position of 75

Fig. 13 to that of Fig. 14 by the pawl 30d, but the pawl 30e is also held outwardly, and in effect bridges across and closes the notch 28e, so that the lug 45b cannot move inward from the position of Fig. 14 to that of Fig. 15 at this notch, but is compelled to continue out of engagement with the penny ratchet 26 until the final notch 28f is reached.

Thus, when the presence of a five cent piece causes the pawl 30c to release the lug 45b at radius *j* (Fig. 12), this lug 45b moves inward again at radius *m*, a distance of five teeth on the penny ratchet 26. Correspondingly, when a ten cent piece effects such a release at radius *f*, restoration occurs at radius *h*, after movement of the parts to an arc representing ten teeth; with a twenty-five cent piece, the release occurs at radius *l*, and restoration at radius *n*; while with a fifty cent piece, release occurs at radius *l*, and restoration at radius *q*, since the pawl 30e is effective adjacent radius *o* to prevent a restoration along radius *n*. The general position at which the detent 45 is operated is indicated by the radius *b*.

Thus, it will be seen that the manipulations involving each coin effect a sizing operation by which the coin causes selection of proper means for releasing a detent, and then restoring the detent to detaining position after the register system has been moved a distance corresponding to the denomination of the coin.

In some instances, this inward movement of the lug 45b from the larger diameter of plate 28 into the notch, for determining the end of the movement of the penny ratchet 26, occurs while the coin is still detained in the coin pocket. Thereafter, the movement of the drum brings the opening 33a opposite the opening 11x, and the spring 31 then operates to restore the sizing lever 35 to its former position, and the coin passes into the box 10. The revolute drum, however, is still free to move in a forward direction, as the ramp 11y depresses the nose 35a sufficiently to permit this continued rotation. Finally, however, the nose 35a escapes into the opening 11a, and is detained by the end wall thereof. The parts are now in initial position, ready for insertion of a new coin.

The mechanical effects have comprised the insertion of a coin and the rotation of the crank arm 17 through a single revolution. The visible effect is the movement of the long hand C opposite the indicia on the dial 16 from the former reading to one which is greater by the denomination of the coin which has been registered. If the value of the coin is such that the long hand moves past "0", the lug 26b of the penny ratchet 26 operates, as described in connection with Fig. 4 and 5, to accomplish a movement of the dollar ratchet 22 and therewith a movement of the short hand D from one dollar unit to the next, with respect to the dial indicia.

A modified form of structure is indicated in Figs. 20 and 21, substantially corresponding, respectively, to Figs. 5, 6, and in Fig. 22 shows a different moved position of the parts in Fig. 20.

In this form, the outer casing 11 contains a revolute drum with an end surface 32 as before, this end surface having a forwardly projecting lug 32k. The revolute drum includes the structures comprising the sizing lever, coin pocket, etc., along with the detent nose 35a. The operation of the sizing lever produces a rocking of the cam 31k, Fig. 21, which is distinguished from the cam 31 of Fig. 8 in that it has only three humps. The structure is intended only to accept and register

coins having the denomination of five, ten, twenty-five and fifty cents. Hence, it has four pawls, comprising the pawl 130b which is actuated for a ten cent piece, the pawl 130c which is actuated for a five cent piece, the pawl 130d which is actuated for a twenty-five cent piece, and the pawl 130e which is only actuated for a fifty cent piece. Correspondingly, the teeth on the penny ratchet 126 (Figs. 20 and 22) are of a length which is five times that of the teeth of the penny ratchet 26 of Fig. 5, as the shortest angular movement will correspond to five cents on the dial, and this dial indicates a dollar, or twenty such movements. Further, this modified form is intended to register to five dollars only, and not to ten, by a full revolution of the short hand B. For this purpose, the penny ratchet 126 is provided with two lugs 26b, so that the short hand moves by half the arc from "0" to "1", for example, when fifty cents has been registered by the long hand, and then completes the other half of this arc when the full dollar has been registered. The method of operation in this dollar transfer is obvious from the disclosure with respect to Fig. 5.

In this form, the fixed support 11m is inside the casing 11 and pivotally supports the detent or locking arm 145, which in this form need only make a rocking motion toward and from the shaft portion 28b. It has a lug which extends toward the plate 32 for engaging the teeth of the penny ratchet 126, and for actuation by the successive pawls 130b, 130c, etc. The structure 11m also engages the rocker 128, which has a lug 128a directed toward the end of the detent 145. The structure 11m is preferably secured to the casing 11 adjacent its connection to the resilient detent arm 145, and is free at the other end and operates upon the rocker 128 to press the latter toward the end of the arm 145.

The registering operation of the penny ratchet in Figs. 20 to 22 is as follows: when a coin is inserted, the cam 31k is rocked and its humps accomplish a selection as before, but in this form of the structure, only a single pawl is selected by any one coin. As the revolute drum is rotated, the pawls are carried along therewith, one of these pawls having been selected by the corresponding coin. The detent arm 145 is holding the penny ratchet 126 against driving through a friction member corresponding to the friction member 27 of Fig. 6. Ultimately, the selected pawl 130b . . . 130e engages the lug on the detent lever 145 and presses the latter outward, out of engagement with the penny ratchet 126, and the rocker 128 now slips inward and presents its lug 128a to hold the detent 145 out of engagement (Fig. 22) with the ratchet 126. The penny ratchet 126 is now turned through the friction member. Finally, the lug 32k encounters the rocker 128 and moves this rocker in a counter-clockwise direction from the position of Fig. 22, so that the detent 145 can return to the position of Fig. 20, and again engage and stop the penny ratchet 126. The rocker 128 has a notch 128b (Fig. 23), which permits the lug 32k to escape past it, whereupon the rocker is returned by the resiliency of the mounting 11m.

It will be noted that the angular distance, around the periphery of the revolute drum, from the point at which a pawl 130b, etc., operates, to the radial line which this point attains when the lug 32k disengages the rocker 128, is equivalent to the denomination of the coin corresponding to such pawl.

The operation of releasing the coin from the 75

coin pocket, and other features, are essentially the same as described for the first modification.

It is obvious that the invention may be practiced in many other ways without departing from the scope of the appended claims.

What I claim is:

1. In a registering bank, a casing; a member revoluble in the casing and including a coin holder for receiving coins of various denominations, a cam member selectively actuated in accordance with the denomination of the coin and having selecting means thereon positioned during such actuation, means responsive to the size of the coin for actuating the cam member and mounted on said revoluble member, and selector devices controlled by the selecting means on the cam member; registering means including a registering member to be advanced in accordance with the denomination of the coin, and a friction device for causing said registering member to turn with the revoluble member; a detent on the casing for holding the registering member against advancement and operated for releasing the registering member by a selector device when the latter is under control of the cam member, and means on the revoluble member for restoring the detent for holding the registering member after the latter has been advanced a distance corresponding to the denomination of the coin positioned in the revoluble member.

2. A bank as in claim 1, in which the coin-responsive means is a coin sizing lever connected for moving the cam member and a link, and in which the revoluble member and cam member turn about coincident axes, and the coin sizing lever turns about an axis parallel to and spaced from said coincident axes and is connected by said link with the cam member.

3. In a registering bank, a casing, a member revoluble in the casing and including a coin holder for receiving coins of various denominations and having mounted thereon selecting devices, means responsive to the size of the coin for controlling the movement of said selecting devices and selectively moved in accordance with the denomination of the coins, a registering member, a friction member for causing said registering member to turn with the revoluble member, a detent on the casing to hold the registering member against advancement, said selecting devices being effective when selectively controlled by said coin-responsive means for disengaging the detent from said registering member, means for preventing re-engagement of the detent, and means on the revoluble member for restoring the detent to initial engaging position after the registering member has been advanced a distance corresponding to the denomination of the coin.

4. A bank as in claim 3, in which the revoluble member has a cam portion for providing said preventing means, and also has another portion for restoring the detent to initial position.

5. A bank as in claim 3, in which the detent is mounted for movement in two planes at an angle to one another, the selecting devices being effective for causing the detent to move in one said plane for disengaging the registering member, means for causing the detent to move in the other plane when so disengaged, said revoluble member having thereon said preventing means, said preventing means being effective for preventing re-engagement of the detent after movement in the other plane until the registering member has been advanced a distance corresponding to the denomination of the coin and

thereupon being effective for re-engagement of the detent by movement thereof in said one plane, and said revoluble member also including said restoring means for moving the detent in the other plane whereby to restore the detent to 5 initial position.

6. In a registering bank, a casing; a member revoluble in the casing and including a coin holder for receiving coins of various denominations, selector devices mounted for movement on 10 said revoluble member, and means responsive to the size of the coin for actuating the selector devices; a registering member to be advanced in accordance with the denomination of the coins, and a friction device for causing said registering 15 member to turn with the revoluble member; a detent on the casing to hold the registering member against advancement, the selector devices being effective when selected for disengaging the detent from the registering member, latching 20 means on the casing for preventing re-engagement of the detent, and means on the revoluble member for operating the latching means whereby to effect re-engagement of the detent with the registering member.

25

7. A bank as in claim 6, in which said latch-operating means comprises a single projection on the revoluble member for engaging the latching means, and in which the selector devices are pivoted on the revoluble member and positioned 30 in advance of said latch-operating projection for disengaging the detent from the registering member a distance in advance of the latch releasing movement of the projection which is equivalent to the denomination of the coin.

35

8. In a registering bank, a casing; a member revoluble in the casing and including a coin holder for receiving coins of various denominations, a coin sizing lever pivoted on said revoluble member, a cam member connected to said coin 40 sizing lever and selectively actuated in accordance with the denomination of the coin and including a plurality of selecting means, and selector devices eccentrically pivoted on said revoluble member and having portions selectively engaged 45 by a corresponding selecting means on the cam member in accordance with the denomination of the coin in said receiving means; a registering member and a friction device for causing said registering member to turn with the revoluble 50 member, a detent on the casing for holding the registering member against advancement and having portions in the path of movement of the selector devices so that the selector device which has been selected will be effective to disengage 55 the detent from the registering member, and means on the revoluble member for restoring the detent to holding engagement with the registering member after the latter has been advanced a 60 distance corresponding to the denomination of the coin positioned in the revoluble member.

55

9. In a registering bank, a casing, a member revoluble in the casing and including a coin holder for receiving coins of various denominations, selector devices eccentrically pivoted on the 65 revoluble member and selected according to the denomination of the coin in the revoluble member, means responsive to the size of the coin for actuating the selector devices, a registering member, a friction device for causing said totalizing 70 member to turn with the revoluble member, a detent on the casing for engaging the registering member and operating with the selector devices to be disengaged from the registering member, said revoluble member being formed with a plu- 75

rality of cam surfaces for maintaining the detent out of engagement with the registering member, each said cam surface having a length corresponding to the denomination of a coin, and means fixed to the revolute member at the end of each said cam surface for restoring the detent to its initial position of engagement with the registering member.

10. A registering bank comprising a casing and a revolute member in said casing, said member having rigid therewith a first end surface and a supporting plate having a second end surface spaced from said first end surface, said supporting plate having its periphery formed with cam surfaces and with notches, selector devices pivoted on said revolute member, coin responsive means on the revolute member for selectively controlling the selector devices, a registering member, a detent mounted on the casing, friction means for driving the registering member when the revolute member is rotated, said detent normally being engaged with said second surface, said revolute member being effective in movement for causing a selected selector device to cause the detent to leave said second surface and pass onto said first surface and therewith be held by said cam portion out of engagement with the registering member so that the latter may be turned from said friction member, the notch on the supporting plate at the end of the corresponding cam portion permitting the re-engagement of the detent with the registering member, and means located at the end of the notch for returning the detent from engagement with said first surface to its initial position of engagement with said second surface.

11. In a registering bank, a casing, a revolute member having an end wall, a supporting plate forming part of the revolute member and spaced from said end wall, a cam member positioned between the end wall and the supporting plate and revolute about the same axis as the revolute member and also being movable about said axis independently of the revolute member, said cam member having a plurality of selecting means thereon, coin sizing means for producing such a relative movement of the cam member of an amount which is determined in accordance with the denomination of the coin being sized whereby to position for effective operation a corresponding selecting means, a plurality of selector devices pivoted on the revolute member and having projections extending into the path of movement of the cam member, so that said selecting means on the cam member effectively selects among the selector devices in accordance with the denomination of the coin, a registering member, a friction member for driving said registering member from the revolute member, and a detent for holding the registering member against movement, said selector devices being effective for disengaging the detent.

12. A registering bank comprising a casing, a revolute member including a coin holder and

having a sizing means mounted thereon, selector devices mounted on said revolute member, said sizing means being effective for selectively limiting the movement of a selected selector device according to the denomination of the coin being sized, a registering member, a friction member for driving the registering member from said revolute member, a detent on the casing for holding the registering member against movement, said revolute member having a first end surface and a second end surface axially spaced therefrom, the detent being engageable with one or the other of said surfaces, said revolute member also providing peripheral portions of lengths equivalent to the denominations of coins, each said peripheral portion terminating at a notch by which said second surface is interrupted along the path of relative movement of the detent, ramps extending from said first surface to said second surface at one end of each notch for restoring the detent from said first surface to said second surface, the selector devices being effective for displacing the detent from engagement with the registering member and moving it to a position opposite the corresponding peripheral portion, and means for moving the detent from alignment with the second surface into engagement with said first surface so that the detent is held by the corresponding peripheral portion against re-engagement with the registering member until the corresponding notch is presented opposite the detent.

13. A registering bank comprising a casing, a revolute member including a coin holder and having a sizing means mounted thereon, selector devices mounted on said revolute member, said sizing means being connected and arranged to be effective for selectively limiting the movement of a selected selector device according to the denomination of the coin being sized, selector devices for cooperation with the cam, one of said selector devices being actuated for each of two coins of different denomination and another selector device being actuated only by the one of said coins which is of greater denomination, a registering member, a detent for holding the registering member against movement, means for advancing the registering member with the revolute member, a detent controlling member, said selector devices being effective for controlling the detent whereby at the first contact of the detent and a selecting device, the detent is disengaged from the registering member, means for preventing re-engagement of the detent with the registering member until the registering member has been advanced through a distance corresponding to the denomination of the coin of smaller value, said second selector device being effective with the presence of a coin of the larger denomination for preventing re-engagement of the detent with the registering member at the position of re-engagement for the coin of lesser denomination.

HARRY T. KINGSBURY.
